H. P. SLEEPER

RELAY SYSTEM

Filed April 11, 1922

UNITED STATES PATENT OFFICE.

HARVEY P. SLEEPER, OF WILKINSBURG, PENNSYLVANIA, ASSIGNOR TO WESTINGHOUSE ELECTRIC & MANUFACTURING COMPANY, A CORPORATION OF PENNSYLVANIA.

RELAY SYSTEM.

Application filed April 11, 1922. Serial No. 551,448.

My invention relates to electrical protective systems and particularly to relay systems for protecting distribution systems.

One object of my invention is to provide a relay system for protecting a plurality of parallel-connected transmission circuits extending between two predetermined points of an electrical system.

Another object of my invention is to provide a system, of the above-indicated character, whereby the transmission systems may be protected according to a predetermined unbalance between the currents traversing the respective circuits arranged in pairs.

Another object of my invention is to provide a relay system, of the above-indicated character, in which a relay, that is associated with two predetermined circuits to control the disconnection of the circuits upon the occurrence of an unbalance exceeding a predetermined amount between the circuit currents, shall be rendered inoperative to control the associated circuit upon the disconnection of either circuit from the system by reason of a condition in that circuit producing an unbalance between the currents traversing the associated circuit.

Another object of my invention is to provide a system, of the above-indicated character, in which the relay shall selectively control the disconnection of either associated circuit upon the occurrence of such conditions in either circuit as would cause a variation beyond a predetermined amount between the circuit currents.

A further object of my invention is to provide a system, of the above-indicated character, in which the control balance relay shall be not only selective in its operation but shall also embody an inverse-time element in its operation.

United States Patent No. 1,286,415, issued Dec. 3, 1918 to F. E. Ricketts, and assigned to the Westinghouse Electric and Manufacturing Company, discloses an induction disc-type relay embodying an inverse-time function in its operation that is obtained and controlled by means of a saturable transformer that operates to control the torque developed in the relay.

The saturable transformer permits a torque to be developed in the relay that is proportional to the value of the current traversing the relay up to a predetermined value at which the transformer becomes

saturated. When the current traversing the relay exceeds the value at which the transformer becomes saturated, the torque developed in the relay remains constant, irrespective of increase in the value of current traversing the relay, by reason of the regulating effect of the saturated transformer.

In practicing my invention, I employ a saturable transformer, or torque compensator, as it is commonly known and which is described in the above-mentioned Ricketts' patent, and apply it to a relay of the induction type in such manner as to cause the relay to have both a directional and a time-70 element feature.

The single figure of the accompanying drawing is a diagrammatic view of a portion of an electrical system illustrating three parallel-connected conductors of respective transmission circuits and a relay system for protecting such circuits upon the occurrence of such faults in any one of the conductors as would cause an increase, decrease or reversal of current that would tend to disturb 80 a predetermined balance between the currents that might traverse the respective circuits.

As is illustrated in the accompanying drawing, energy is supplied from a source of 85 electromotive force 10 to a plurality of transmission circuits 11, 12 and 13 through associated circuit interrupters 14, 15 and 16, respectively.

The circuit 11 is provided with an over-load relay 17 and a balance relay 18. The circuit 12 is similarly provided with an over-load relay 19 and a balance relay 20, and the circuit 13 is likewise provided with an over-load relay 21 and a balance relay 22.

The relays are inductively energized from the respective circuits through current transformers 23, 24 and 25, respectively. The over-load relays 17, 19 and 21 are adapted to close their respective switches 26, 27 and 28 100 when energized to a predetermined degree and for a predetermined interval of time corresponding thereto, irrespective of the direction of power traversing the associated circuits.

The balance relays 18, 20 and 22 comprise, respectively, a magnetizable core member 30, provided with two differentially-acting windings 31 and 32, and a selectively energized winding 33 that is adapted to co- 110

operate with the differentially-acting windings to control the direction of movement of a movable disc member 34.

The disc member 34 controls a bridging member 35 that is adapted, when actuated in one direction, to engage two contact members 36 and, when actuated in the other direction, to engage two contact members 37. The balance relays further comprise, respectively, a saturable transformer 38 that is provided with two differentially-acting primary windings 39 and 40 and a single secondary winding 41 that is connected to the relay winding 33.

The overload relays 17, 19 and 21 are arranged to control the respective circuits associated therewith. Each of the balance relays 18, 20 and 22, however, is arranged to control two of the transmission circuits. The balance relay 18 controls the circuits 11 and 12, the balance relay 20 controls the circuits 12 and 13 and the balance relay 22 controls the circuits 11 and 13.

Upon the occurrence of faulty conditions in one of the circuits, the relays will selectively control the operation of the associated interrupter. Each of the interrupters is provided with a trip coil 42 and three interlock switches 43, 44 and 45.

In order to indicate to an attendant in the station the automatic disconnection of a circuit by reason of a faulty condition, a bell, or other indicating device, 46 is employed which is operated whenever one of the interrupters is automatically opened. A transfer relay 47 is employed to control the circuit of the bell, or other indicating device.

The relay 47 comprises a switch 48 that normally is closed and a switch 49 that normally is open. The relay further comprises an operating coil 50 which, when energized, actuates the switches 48 and 49 to opposite positions, at which positions the switches are maintained by a latching member 51. The latching member 51 is actuated to permit the resetting of the relay in its initial position upon the energization of a resetting coil 52. A push-button switch 53 is provided to control the circuit of the resetting coil.

By tracing the circuits of the operating coils of the balance relays, it will be noted that the relays are energized in accordance with the degree of unbalance between the currents traversing the associated circuits. In considering the connections of the relay 18, for example, it will be observed that the windings 31 and 39 are energized from the current transformer 23, whereas the windings 32 and 40 are energized from the current transformer 24. The windings 39 and 40 are connected in their respective circuits to be differentially effective in energizing the secondary winding 41 of the saturable transformer.

The windings 31 and 32 are similarly dif-

ferentially effective in maintaining a flux distribution in the magnetizable core member 30. Since the winding 41 is energized in accordance with the difference between the degree of energization of the windings 39 and 40, the direction of the current traversing the winding 41 will depend upon which of the windings 39 or 40 is energized to a greater degree. The flux established by the current traversing the winding 33 will thereupon co-operate with the flux established by the winding 31 or 32 to control the direction of movement of the disc member 34, depending upon which set of windings 31 and 39 or 32 and 40 is energized to a greater degree.

The saturable transformer 38 introduces a time element in the operation of the balance relay 18 by reason of its saturable character and its limiting effect upon the value of the current that may be caused to traverse the circuit including the secondary winding 41.

The transformer 38 also serves to introduce an electrical angular displacement between the flux established by the winding 33 and the resultant flux established by the differentially-acting windings 31 and 32, thereby rendering the induction relay 18 operative. The necessity for shading pole pieces or other corresponding means for introducing an angular displacement between two of the fluxes to produce a rotative torque in the disc member is thus obviated.

The interrupters 14, 15 and 16, when closed, effect the closing of the associated interlock switches 43, 44 and 45 to complete the various circuits controlled thereby. The switches 43 of the interrupters control the circuit of the associated trip coil 42. The switches 45 of the interrupters 14 and 16, when closed, control the energizing circuit for the control switch of the balance relay 22. The switches 44 of the interrupters 15 and 16 control the energizing circuit for the control switch of the balance relay 20 and, similarly, the interlock switch 44 of the interrupter 14 and the switch 45 of the interrupter 15 control the energizing circuit of the balance relay 18. The switch 45 of the interrupter 14 similarly controls the energizing circuit for the overload relay 17. Similarly, the switch 45 of the interrupter 15 and the switch 44 of the interrupter 16 control the energizing circuits for the switches of the associated overload relays 19 and 21, respectively.

If the interrupters 14, 15 and 16 are all closed to connect the feeder or transmission circuits to the system, and a fault should occur upon the conductor 11 that would cause such an unbalance between the currents traversing the conductors 11 and 12 as to exceed a predetermined ratio between such currents, the windings 39 and 31 would be ener-

gized to a greater degree than the windings 32 and 40. The balance relay would thereupon be energized to actuate the disc member 34 to effect the engagement of the contact members 36 by the bridging member 35. A circuit would thereupon be completed from the positive conductor of the control circuit through the switch 45 of the interrupter 15, the switch 44 of interrupter 14, the switch 35, the contact members 36, thence through two circuits in parallel, one including the trip coil 42 and the other including the operating coil 50 of the transfer relay 47, controlling the bell 46, to the negative conductor of the control circuit.

The interrupter 14 would thereupon be opened and the relay 47 would be actuated to its biased position to complete the circuit of the bell 46, thereby signalling to the station attendant that a circuit had been automatically disconnected from the system by reason of a faulty condition thereon. By depressing the push-button switch 53, the attendant can reset the relay 47 to render it operable for subsequent operation.

Upon the opening of the circuit interrupter 14 to disconnect the circuit 11 from the source of energy 10, the switch 44 is opened. The balance relay 18 is then, therefore, inoperative to control the interrupter 15 of the circuit 12. Balance protection is still obtained, however, between the circuits 12 and 13 by means of the balance relay 20, since the windings 31 and 39 of that relay are energized from the current transformer 24 and the windings 32 and 40 are energized from the current transformer 25. If the circuit 13 should now be disconnected by reason of abnormal conditions therein, the interrupter 16 would be opened and the control circuits of all of the balance relays would be open circuited and the relays rendered inoperative to control any of the circuits. Under such conditions, the overload relay 19 would provide overload protection for the circuit 12.

So long as balanced current conditions obtain in the three or more transmission circuits, the balance relays will not operate to disconnect any of the circuits, irrespective of the amount of current traversing the same. Under such conditions, the overload relays provide overload protection for the respective circuits.

It will be noted that a balance relay is associated with each two successive transmission circuits arranged as a pair of circuits to be protected by the associated relay. For the sake of simplicity, I have shown but one phase of the system involved. Similar protection would be provided for the other phases of the circuits to be protected.

While I have shown a system of protection containing a particular type of relay, I do not limit my invention to the partic-

ular relays that are illustrated or to the particular arrangement thereof, since modifications may be made therein without departing from the spirit and scope of the appended claims.

I claim as my invention:

1. The combination with a plurality of parallel-connected conductors between two points of an electrical system and circuit interrupters for the respective conductors, of an induction relay for selectively controlling either interrupter depending upon the occurrence of a fault thereon affecting a predetermined ratio between the currents normally traversing the conductors, said relay comprising a controlling member movable in two directions, two differentially-acting windings, a winding co-operating with the differential windings to actuate the movable member in one direction or the other depending upon the degree of energization of the differentially-acting windings and means for energizing the said winding in accordance with the variation from a predetermined ratio of the currents traversing the pair of conductors, said means serving also to introduce an electrical angular displacement between the magnetic flux established by the said winding and the flux established by the differentially-acting windings, the fluxes co-operating to effect movement of the movable member, in a time interval dependent upon the degree of energization of said winding.

2. The combination with a plurality of parallel-connected conductors and circuit interrupters for the respective conductors, of means normally balanced when the currents traversing the conductors bear predetermined relations to each other and means comprising a saturated transformer controlled by currents proportional to the main currents traversing the conductors for controlling said balanced means and for introducing a time element and a directional element in the operation thereof.

3. In an electrical system, the combination with a plurality of parallel circuit conductors, circuit interrupters therefor and current transformers energized therefrom, of means for selectively controlling the interrupters upon the occurrence of a fault in one of the conductors tending to affect a predetermined ratio between the currents of the several circuits comprising a balance relay provided with two windings, each energized from a current transformer in each conductor, and a co-operating winding for actuating the relay to select one or the other circuit interrupter, and a control element also energized from the same current transformers for controlling the energization of the co-operating windings to introduce a direction selective action and an inverse time interval in the relays responsiveness.

4. In an electrical system, the combination

with a plurality of parallel circuit conductors, circuit interrupters therefor and current transformers energized therefrom, of means for selectively controlling the interrupters upon the occurrence of a fault in one of the conductors tending to affect a predetermined ratio between the currents of the several circuits comprising a balance relay provided with two windings, each energized from a current transformer in each conductor, and a co-operating winding for actuating the relay to select one or the other circuit interrupter, and means for influencing said winding comprising an element responsive to the difference between the two circuit currents and an element associated therewith for introducing a saturating characteristic to the influence of said element upon the winding thereby to introduce a selective

and time delay action in the co-operation between said winding and the two differential windings. 20

5. An electric protective relay comprising an electromagnet provided with two windings differentially operative and adapted to be connected to two normally current-balanced circuits, a movable member, a winding for co-operating with the differential windings to actuate the movable member in one direction or the other, and means co-operative with the several windings for influencing the selective action and introducing a time element in the response. 25 30

In testimony whereof, I have hereunto
subscribed my name this 31st day of March, 35
1922.

HARVEY P. SLEEPER.
